(57) **CLAIM**

The ornamental design for an animal cage, as shown.

DESCRIPTION

FIG. 1 is a perspective view of an animal cage of the present invention;

FIG. 2 is a front view thereof;

FIG. 3 is a rear view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is an exploded view of the animal cage herein.

The dot-dashed lines in the drawings illustrate shading and form no part of the claimed design.
